Primary Examiner — George D. Kirschbaum*Assistant Examiner* — Joseph J Kukella(57) **CLAIM**

The ornamental design for a construction toy set, as shown and described.

DESCRIPTION

The patent or application file contains at least one drawing executed in color. Copies of this patent or patent application publication with color drawing(s) will be provided by the Office upon request and payment of the necessary fee.

1. Construction toy set

1.1 : Perspective

1.2 : Perspective

1.3 : Perspective

1.4 : Perspective

1.5 : Top

The product is characterized by the following features of the outward appearance: the construction toy set consists of individual components that connect together in a single play concept, the individual components having the 3-d geometric shapes of regular prisms of equal height with polygonal bases, except for one component of the set having a spheroid shape; the individual components are of comparable proportional sizes.
